Primary Examiner — Patricia A Palasik(74) *Attorney, Agent, or Firm* — Myers Bigel, P.A.(57) **CLAIM**

The ornamental design for a logistics robot, as shown and described.

DESCRIPTION

FIG. 1 is a top, front, left side perspective view of a logistics robot showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in FIG. 7 depict portions of the logistics robot that form no part of the claimed design.

1 Claim, 5 Drawing Sheets(56)
